UNITED STATES PATENT OFFICE.

JOHAN G. LENHART AND CHARLES F. RISTINE, OF BELLINGHAM, WASHINGTON.

SUPPLY-HOLDER FOR SCHOOL-DESKS.

1,202,743.

Specification of Letters Patent. Patented Oct. 24, 1916.

Application filed September 27, 1913. Serial No. 792,176.

To all whom it may concern:

Be it known that we, JOHAN G. LENHART and CHARLES F. RISTINE, citizens of the United States, residing at Bellingham, in the county of Whatcom and State of Washington, have invented new and useful Improvements in Supply-Holders for School-Desks, of which the following is a specification.

10 This invention relates to supply holders for school desks or the like for holding supplies, such as pencils, pens, sponges or the like; and it has for its primary object the provision of an article of this character 15 which may be applied to any well known form of school desk and arranged thereon so that the supplies are readily accessible when needed.

20 A further object of the invention is the provision of a supply holder which may be stamped up from a single piece of sheet metal and arranged at the corners with rolled edges of adjacent walls so as to form closed continuous joints whereby to prevent leakage.

A still further object of the invention is the provision of a supply holder that may be washed when desired and maintained in a highly sanitary condition.

25 With these and other objects in view, the invention consists of certain novel features of construction, combination and arrangement of parts, as will be hereinafter described and claimed.

30 In the accompanying drawings, Figure 1 is a perspective view of a desk, showing the application of the supply holder thereto; Fig. 2 is a plan view of the blank from which the holder is constructed; Fig. 3 is 40 a horizontal section through the holder; and Fig. 4 is a vertical section therethrough.

The holder is constructed of a single blank of sheet material stamped to provide a bottom 1, a front wall 2, connecting end 45 walls 3 and an attaching back wall 4, the latter being extended above the plane of the open end of the receptacle and provided at suitable points with openings 5 by means of which fastening devices 6 may be extended through said back wall and securely engaged in the adjacent body 6 of the desk

7 herein conventionally illustrated. The upper edges of the walls 2 and 3 are rolled throughout their length, as at 8, while at the ends all of the walls are extended beyond the rolled portions, and as illustrated the extended portions of the front wall 2 are curved forwardly, as at 9 and then outwardly at 10 and crimped with and securely pressed into locking engagement with similar portions 11 of the end walls 3. The rear wall 4 is provided with rearwardly-extending portions 12 and terminals 13 that are interfolded with corresponding portions 14 at the opposite vertical ends of the walls 3. 65 In this manner all of the vertical joints at the points of connection with the various walls with each other are connected in a way which will render the holder liquid-tight at the joints and prevent leakage. 70 When the end walls 3 are interlocked with the front and back walls, the flange 8 formed on the front wall 2 is then bent downwardly in a position as shown in Fig. 1, the opposite ends of the flange engaging the portions 75 14 of the end walls to prevent them from becoming disengaged from the rolled edges of the front wall, whereby it will be locked in holder formation.

By connecting the various walls of the 80 receptacle as described the use of solder or other permanent fastenings may be entirely eliminated and at the same time the corners and vertical edges of the receptacle are made smooth so as to prevent the parts from 85 injuring the hands while the receptacle is in use.

From the foregoing description, taken in connection with the accompanying drawings, the construction and operation of the 90 invention will be readily understood without requiring a more extended explanation.

Various changes in the form, proportion and the minor details of construction may be resorted to without departing from the 95 principle or sacrificing any of the advantages of this invention as claimed.

Having thus described our invention, what we claim is:—

100 A receptacle constructed from a single blank of metal and comprising bottom, side and end walls, the side and end walls having

their vertical edges rolled and interfolded with each other, the longitudinal edges of the side walls being provided with flanges, said flanges lying contiguous to the outer 5 faces of the side walls, the opposite ends of the flanges engaging the rolled edges of the end walls whereby the side and end walls will be locked together.

In testimony whereof we affix our signatures in presence of two witnesses.

JOHAN G. LENHART.
CHARLES F. RISTINE.

Witnesses:

VICTOR I. BRADWAY,
J. S. TRUITT.
